UNITED STATES PATENT OFFICE.

CHARLES P. COOPER, OF RUTLAND, VERMONT, ASSIGNOR TO THE CREAMERY PACKAGE MFG. COMPANY, OF CHICAGO, ILLINOIS, A CORPORATION OF ILLINOIS.

BIN.

Application filed May 26, 1921. Serial No. 472,762.

To all whom it may concern:

Be it known that I, CHARLES P. COOPER, a citizen of the United States, residing at Rutland, in the county of Rutland and State of Vermont, have invented certain new and useful Improvements in Bins, of which the following is a specification.

The invention relates to bins or silos and has particular reference to bins of the wooden stave type.

One of the most serious objections to bins or silos constructed from wooden staves is that by reason of the fact that they are made of substantial height and are subjected to severe strains both from internal pressure and from external or wind pressure, they are apt, after the silo has been in use for some time, to lean, twist, blow in, or otherwise become misshapen and distorted.

20 The object of the present invention is to provide a construction for the bin or silo which is capable of effectively overcoming such difficulty, and this is accomplished by providing a specially formed base, of concrete or the like, to which the staves are individually anchored so as to be held against movement either laterally or vertically whereby effectively to resist all lateral strains upon the structure whether internal or external.

25 In the accompanying drawings forming part hereof, I have illustrated a preferred embodiment of my invention. Thus, Figure 1 is a front view of the lower portion of the improved bin partially broken away and in section, and showing the forms in place by means of which the concrete foundation or base is formed. Fig. 2 is a fragmentary vertical sectional view showing a portion of the completed bin having an inner cove formed of concrete and constituting the annular upstanding portion to which the peripheral side wall of the bin is secured. Fig. 3 is a perspective view of the lower end 30 of one of the wooden staves showing one form of anchoring socket.

35 While the drawings illustrate but one embodiment of the invention, it will be understood that various changes in form, arrangement and construction may be adopted without departing from the spirit and scope of the invention as expressed in the appended claims.

The silo comprises a foundation or base 4 annular in form and supporting the pe-

ripheral wall structure consisting of a plurality of staves 5. 6 designates an upstanding annular portion of the base 4, to which the lower ends of the staves are rigidly fastened. This is accomplished through the medium of radial projections 7 entering sockets or recesses 8 provided in the inner sides of the staves at their lower ends. Said projections are held in engagement with such recesses by means of hoops 9.

60 The base 4 is preferably constructed of concrete, the annular portion 6 thereof being preferably made integral with the lower or main portion as shown in Fig. 1. The annular portion 6 is formed of somewhat smaller diameter than the lower portion to provide a shoulder 10 upon which the lower ends of the staves 5 rest. In forming the base 4 with the annular portion 6, suitable formwork is employed in conjunction with the staves themselves. Thus 11 indicates the inner formwork having suitable bracing means 12, and 13 designates the outer formwork which is secured in place in any suitable manner (not shown) and terminates at its upper end substantially flush with the shoulder 10.

65 The staves 5 are of ordinary construction, having parallel interfitting edges, and are recessed at their lower ends prior to being assembled, to provide the sockets or recesses 8. Obviously these recesses may be of any suitable or desired shape and preferably two recesses are provided in each stave at a substantial distance apart longitudinally of the 70 stave.

75 The projections 7, it will be understood, are formed by the concrete entering the recesses 8 as it is being poured, to form the annular portion 6, care being taken that the concrete completely fills said recesses. When, therefore, the lower ends of the staves are clamped snugly around the annular portion 6 by the hoops 9, the projections 7 serve to resist vertical movement of the staves, and the latter, being snugly bound together, coact effectively to resist any tendency of the bin to lean or sway laterally. To enable the hoops 9 thus firmly to clamp the lower ends of the staves to the annular base portion 6, and thereby enable the projections 7 to resist lateral strains, the hoops 9 are preferably made adjustable in any suitable way. Thus, clamping lugs 14 may be employed to which the opposite ends of 80

the hoops are adjustably secured as by means of nuts 15.

When the bin is employed as a silo, it is desirable to provide a concave bottom or cove, which, as shown in Fig. 2, is utilized to provide the annular upstanding portion to which the lower ends of the staves are secured. Thus, referring to Fig. 2, the cove, which is designated 16, is shown as having been formed after the formation of the foundation 4 or separately therefrom. It will be obvious, however, that the cove may be made integral, if desired, and of any preferred form.

15 It will be apparent that I have provided an improved construction for a bin or silo, which is of a very practical character. The construction is exceedingly simple and yet is exceedingly effective as a means for overcoming the objection to stave silos hereinbefore pointed out. Obviously the interengagement of each of the staves with the base, and especially with longitudinally spaced projections on the annular portion 20 which extends upwardly a substantial distance into the bin, serves to resist lateral pressure upon the bin in a direction perpendicular to the stave, so that with all of the staves firmly bound together, pressure upon any side of the bin is effectively resisted.

I claim as my invention:

1. A bin comprising, in combination, a base, a wall structure formed from a plurality of staves having their lower ends supported by the base, said base having a portion rising therefrom to a substantial height within the wall structure, and means for rigidly securing the lower ends of the staves to said annular portion including interfitting projections and recesses in the annular portion and staves respectively, and means such as hoops for holding said projections and recesses in interengagement.

15 2. A bin in the nature of a silo comprising a base having an upwardly extending portion, and a wall structure formed from a plurality of wooden staves and surrounding at its lower end said upstanding portion of the base, said staves being shaped for inter-locking engagement with integral parts of said upstanding portion of the base whereby to resist lateral strains upon the wall structure.

3. A bin comprising an annular upstanding base portion, a wall structure composed of a plurality of staves, means firmly binding the staves together and around said base portion, said base portion being formed of concrete and said staves each having a plurality of recesses therein spaced apart longitudinally of the stave, which recesses become filled with the concrete when the latter is being poured to form the base whereby to provide radial projections tending to resist lateral strain upon the bin.

4. In a bin, the combination of an upright base portion and a wall structure having a stave formed of wood and having a recess in its lower end, said base being formed of concrete so as to cause a portion thereof to enter the recess in said stave, and means for firmly binding the stave to said base portion.

5. The method of making a wooden stave bin which consists in arranging suitable forms whereby to provide a base of concrete with an upstanding annular portion rising a substantial distance into the wall structure formed by the staves, and anchoring the wall structure to the base by tamping portions of the concrete as the latter is poured to form the upstanding base portion, into recesses provided in the lower ends of the staves and by binding the lower ends of the staves together and around said upstanding base portion.

In testimony whereof, I have hereunto set my hand.

CHARLES P. COOPER.
